UNITED STATES PATENT OFFICE.

JOHN KIRBY, JR., OF DAYTON, OHIO, ASSIGNOR TO THE UNITED STATES HEAD-LIGHT COMPANY, OF BUFFALO, NEW YORK, A CORPORATION OF NEW YORK.

FOCUSING DEVICE.

1,319,874.

Specification of Letters Patent. Patented Oct. 28, 1919.

Application filed October 15, 1918. Serial No. 258,254.

To all whom it may concern:

Be it known that I, JOHN KIRBY, Jr., a citizen of the United States, residing at Dayton, in the county of Montgomery and State of Ohio, have invented a certain new and useful Improvement in Focusing Devices, of which the following is a specification.

My invention relates primarily to electric headlights and has for its purpose to provide mechanism for adjusting the filament of an incandescent lamp to the focal point of a parabolic reflector, as set forth in my pending applications, Serial Number 249,383, filed August 12, 1918, Serial Number 251,913, filed August 29, 1918, and Serial Number 253,678, filed September 12, 1918, from all of which my present invention differentiates in certain particulars not described, or claimed therein but which will be made clear in this specification and pointed out in the claims at the end thereof.

In headlights of the type to which my invention is applicable it is essential that the center of illumination be located with accuracy in respect of the focal point of the reflector and to this end my invention consists in the novel construction and combination of parts hereinafter more fully set forth and claimed.

The invention is illustrated in the accompanying drawings, which constitute a part of this specification and in which Figure 1 is a side view showing the device, assembled and mounted in its position with relation to the reflector, the same being shown partly in full and partly in section; Fig. 2 is a rear view of the same, except that the reflector and its supporting stand are removed; Fig. 3 is a rear view of the ball holder and attachments thereto, the upper portion being broken away and sectioned through the center thereof; Fig. 4 is a sectional view of the ball as shown in Fig. 1; Fig. 5 is a sectional view of the ball through the line AA Fig. 1; Fig. 6 is a sectional view of the ball below the line BB Fig. 1; Fig. 7 is a perspective view of the separate member which carries the screws for securing the socket holder in position in the ball; Fig. 8 shows a modification of the ball shown in Fig. 1; Fig. 9 shows a modified type of ball, in section through the center thereof, the same being shown hollow with lugs formed integral therewith for receiving the retaining screws.

and Fig. 10 shows a modification of the retaining band.

Like reference numerals indicate corresponding parts throughout the drawings. 1 represents a portion of the reflector, the front end of which may be mounted upon any suitable slide or base, as 2, in the usual manner, not shown. A ring 3 is secured to the rear of the reflector, the apex of which is cut away at 4 leaving an opening corresponding to the inner diameter of the said ring 3. At the bottom of and preferably integral with the said ring 3 there is a laterally disposed arm or bracket extension 5 having a depending screw threaded member 6, which in conjunction with the standard 7 and nuts 8 and 9 constitute means by which the rear end of the reflector is adjustably supported upon the base 2 as more fully described in my previous applications, above referred to. The free end of the bracket 5 is provided with an interiorly screw threaded boss 10 to receive a corresponding exteriorly screw threaded plug 11, having an enlarged head 12, which seats against the upper end of the boss 10, and when these parts are screwed together they may be protected against displacement by means of a pin 13, as shown in Fig. 1. The head 12 is cupped to receive a ball and to it there is securely attached a retaining band or ring 14 having the contour of and forming a support for a spherical element or ball 15, the said band being separated, crosswise thereof, at 16. This band is formed out of sheet metal, preferably by a spinning process which hardens the metal and imparts spring quality thereto so that when the band is separated as above described it becomes self expansible and will spring open sufficiently to allow the ball to be inserted therein and when so placed within the band the latter may be contracted and caused to embrace the ball tightly, by means of a thumb screw 17 having a rounded shoulder 18; a smooth portion 19, and a screw threaded portion 20, the latter engaging a screw threaded lug 21 secured to the band, adjacent its point of separation, and the said smooth portion operating through a clearance perforation in a lug 22, secured to the band opposite the lug 21, the rounded shoulder 18 impinging the outer face of said lug 22. Thus by turning the thumb screw in one direction the ball will be grasped tightly by and held securely within the band, and

2
by turning it in the opposite direction the band will expand by its own spring power and the grip on the ball will be relieved and the same will then be free to be moved, 5 spherically, within the band.

Through the center of the ball there is a channel 23, within which is slidably mounted a tubular member 24, which extends rearwardly from and carries a lamp socket 25, 10 and which is considerably smaller in diameter than the lamp socket, the socket carrying an incandescent lamp 26 having a filament 27, designed to be located central with the focal point of the reflector, indicated at 15 X. Current conveying wires, not shown, pass through the tubular extension for connection with the lamp socket, in the usual manner. Below and in open communication with the channel 23 there is a longitudinal 20 recess 28, which extends through the ball and in which there is located a sheet metal spring 29, having its ends bent downwardly to retain the spring within the recess. Normally, this spring is curved, as indicated 25 by dotted lines in Fig. 1, but when the tubular extension is in its place the spring is forced downward, between its ends, and exerts yielding pressure on the said extension, which prevents movement thereof except 30 during the application of manual effort when adjustment forward or backward is being made.

The extension 24 is preferably square in cross section, and it is provided, at its free 35 end, with a rounded collar 30 for convenience in adjusting the same.

Immediately above and parallel with the channel 23, and opening therein, there is an upper channel 31, which extends through 40 the ball, the latter being cut away thereabove, forming spaces 32, 32^a and shoulders 33, 33^a. Within this channel 31 there is fitted a member 34, provided with upwardly extending lugs 35, 35^a which engage the 45 said shoulders and prevent end-wise movement of said member, which is otherwise held in place by means of a screw 36 passing down from and through the top of the ball, the purpose of the member 34 being to receive set screws 37, 37^a, by which the tubular extension 24 may be secured against undue 50 movement after it has been adjusted to its proper relation with the focal point of the reflector. When the screws 37, 37^a are set 55 tension of the spring 29 against the under side of the tubular extension 24 is transmitted to the said screws and prevents undue movement thereof, which is liable to occur by reason of jarring and vibrations incident 60 to a rapidly moving locomotive or other vehicle upon which the headlight may be installed.

In order to prevent the ball from moving about too freely in the band 14 when its grip 65 on the ball is relieved, by turning the thumb

screw 17, the screw plug 11 is provided with a vertical chamber 38, which also extends through and is in open communication with the inside of the band, and located within this chamber there is a coiled spring 39, one 70 end of which bears against the bottom of the chamber while its opposite end bears against the under side of a movable block 40 having its upper end cupped to the contour of the surface of the ball and against which the 75 block is forced by the pressure of the spring, thereby imparting a steady movement to the ball during the operation of adjustment thereof.

It is to be understood that when the device is assembled and mounted in position in the headlight but little adjustment will be required, to accomplish which the operator loosens the thumb screw 17, and the set screws 37, 37^a, and then moves the ball 80 about in its retaining band, or moves the socket extension, 24, forward or backward as may be necessary to bring the lamp filament in proper relation to the focus of the 85 reflector.

In the foregoing, I have described the preferred embodiment of my invention. It is obvious, however, that the details of construction so described, and illustrated in the drawings, may be departed from in various 90 ways without departing from the spirit of the invention, which I do not wish to be understood as limiting to such exact details: For example, the ball is shown in Figs. 1, 4, 5 and 6 as being solid, except as to certain 95 100 cut away portions hereinbefore referred to, this construction being preferable where wood, celulloid or other light material is employed, but when the ball is cast in brass or iron, or other heavy material, it is desirable that its weight be reduced by the coring process, as shown in Figs. 8 and 9. In case the ball is cast in sand and requires finishing to size, the member 34 should be employed in the manner shown in Fig. 1. 110 But where the ball is die-cast and no finishing is required, lugs similar to 35, 35^a may be cast integral with the ball, and the member 34 may be dispensed with, as shown in Fig. 9. Then, again, the retaining band 115 may be formed in two sections, hinged to a screw plug 11^a, as shown in Fig. 10, adapted to engage the boss 10 of the bracket extension 5.

Other modifications obviously may be 120 made without departing from the scope of my invention.

What I claim and desire to secure by Letters Patent is:

1. In a device of the character described, 125 the combination of a retaining band having the contour of and adapted to encircle and support a spherical element therein, an element having a spherical surface operative within said band and provided with a chan- 130

- nel therethrough, a lamp socket carried by a reduced extension member slidably mounted in said channel, means for contracting said band to secure said element therein, and a spring located in and extending through the body of said element adapted to exert pressure against said extension member in opposite direction to that in which the same is adapted to travel.
2. In a device of the character described, the combination of a retaining band having the contour of and adapted to encircle and support a spherical element therein, an element having a spherical surface operative within said band and provided with a channel therethrough, a lamp socket carried by a reduced extension member slidably mounted in said channel, means for contracting said band to secure said element therein, a recess formed in the body of said element longitudinally of and in open communication with said channel, and a spring located in said recess adapted to exert pressure against said extension member in opposite direction to that in which the same is adapted to travel.
3. In a device of the character described, the combination of a retaining band having the contour of and adapted to encircle and support a spherical element therein, an element having a spherical surface operative within said band and provided with a channel therethrough, a lamp socket carried by a reduced extension member slidably mounted in said channel, means for contracting said band to secure said element therein, a spring located in and extending through the body of said element adapted to exert pressure against said extension member in opposite direction to that in which the same is adapted to travel, and means carried by said element to secure said member against movement in said channel.
4. In a device of the character described, the combination of a retaining band having the contour of and adapted to encircle and support a spherical element therein, an element having a spherical surface operative within said band and provided with a channel therethrough, a lamp socket carried by a reduced extension member slidably mounted in said channel, means for contracting said band to secure said element therein, a spring located in and extending through the body of said element adapted to exert pressure against said extension member in opposite direction to that in which the same is adapted to travel, and means carried by said element to secure said member against movement in said channel.
5. In a device of the character described, the combination of a lamp socket carried by a reduced extension member slidably mounted in said channel, means for contracting said band to secure said element therein, a recess formed in the body of said element longitudinally of and in open communication with said channel, a spring located in said recess adapted to exert pressure against said extension member in opposite direction to that in which the same is adapted to travel, and means carried by said element to secure said member against movement in said channel.
6. In a device of the character described, the combination of a single spherical element having a channel therethrough, a lamp socket extension slidably mounted in said channel, a retaining band having the contour of and encircling said element and constituting a support therefor, means for contracting and expanding said band to tighten and loosen said element therein, lugs carried by said element and coöperating with screws to secure said extension against movement in said channel, a recess in open communication with said channel, and a spring located in said recess adapted to exert pressure against said extension.

In testimony whereof I affix my signature in the presence of two witnesses this 30th day of September, 1918.
